UNITED STATES PATENT OFFICE.

OLE H. FOSMOE, OF MUSKEGON, MICHIGAN.

ARCH SUPPORT.

Application filed May 21, 1927. Serial No. 193,248.

This invention relates to improvements in arch supports for the arch of the human instep and it is used for the cure of what is known as "flat-foot" and for other deformities of the foot.

One object is to provide a device of this class that is simple in construction, efficient in operation, durable, and cheap to manufacture.

10 With the foregoing and other objects in view the invention consists in the combination and arrangement of parts to be herein-after fully described, particularly pointed out in the appended claim and illustrated in 15 the accompanying drawing which forms a part of this application and in which—

Fig. 1 is a perspective view of the arch support.

20 Fig. 2 is an inverted perspective view of Fig. 1.

Fig. 3 is a longitudinal sectional view through the support.

Like reference characters denote corresponding parts throughout the several views.

25 The present invention comprises a leather cushion formed to fit the foot and it has adjustable features whereby it may be made to fit feet of different sizes or shapes and to fit the foot as improvement therein is made 30 and deformities corrected due to the use of the support.

The support is formed, moreover, with a portion scientifically designed to support the foot between the balls thereof. Means to 35 prevent the foot from "turning" are also provided. Most beneficial results can be obtained where injury has been done to the foot by wearing improperly shaped shoes that tend to throw the foot off-balance and 40 so cause deformities.

The reference numeral 1 denotes what may be termed the body of the support and it is arched throughout its longitudinal central

portion and formed with upturned lateral edges 2 and with a reinforced tongue 3 that 45 extends forwardly from the central body portion to support the foot between the balls thereof.

A metal spring 4 formed with a smooth rounded periphery is secured at its ends by 50 brads or other fastening means 5 to the body 1 so that the central portion of the spring is spaced away from the arched portion of said body, one end of said spring being contiguous to the said tongue 3 and 55 the other to the heel portion of said body.

One or two adjustable wedge pads 6 of leather are adapted for insertion between the spring 4 and the body 1 at the arched portion thereof, said pad or pads being 60 adjustable longitudinally of the body to afford a positive support at such point as may be desired.

What is claimed is:—

In an arch support, a body portion having 65 narrow ends and a materially widened intermediate portion, said intermediate portion being arched from said ends, said widened intermediate portion terminating in substantially similar upturned sides, a tongue 70 formed by the extension of said body portion beyond said upturned edges, a spring extending longitudinally and centrally of said body portion and spanning the arched portion thereof, the ends of said spring 75 being secured to said body portion, and a pad interposed between said spring and the arched part of said body portion for frictional engagement with said members, said pad being yieldingly movable longitudinally 80 of said members, substantially as and for the purpose set forth.

In testimony that I claim the foregoing as my own I have hereto affixed my signature.

OLE H. FOSMOE.
